UNITED STATES PATENT OFFICE.

NICOLA MASTROMARINO, OF BOSTON, MASSACHUSETTS.

WASHING MACHINE.

Application filed July 25, 1923. Serial No. 853,895.

To all whom it may concern:

Be it known that I, NICOLA MASTROMARINO, a citizen of the United States, residing at Boston, in the county of Suffolk, State of Massachusetts, have invented a certain new and useful Improvement in Washing Machines, of which the following is a specification, reference being had therein to the accompanying drawings.

10 The invention relates to a new and useful improvement in washing machines. The object of the invention is to provide a washing machine of simple construction that may be readily connected up with any suitable 15 source of water supply for furnishing water and with suitable mechanism for heating the water when desired. Another object of the invention is to mount the machine in a cabinet which may be readily moved about 20 to any location desired without disturbance of the mechanism and so constructed that it may be readily connected up with driving mechanism, water supply and source of heat. Another object of the invention is to 25 provide means whereby the clothes after being washed may be squeezed to press the water out of them in the same receptacle in which they are washed. Other objects of the invention will be more fully set forth 30 hereinafter.

One feature of the invention consists in providing a rotary drum which serves as a tub in which the clothes are tumbled while being washed and mounted in a water tank, 35 the drum being apertured in such manner that water will freely circulate through the drum during the rotation of the drum.

Another feature of the invention consists in providing a movable partition in the 40 drum which may be opened so as to make the two compartments into one in which the clothes are tumbled during the washing operation and which may be closed at will to divide the drum into two compartments 45 when the rotation of the drum is stopped, one of which will contain the clothes. The drum may be turned so that the compartment containing the clothes will be at the top, the clothes then resting on the partition 50 as a bottom while the water drains through the partition into the lower compartment of the drum and out through the drum into the tank.

Another feature of the invention consists 55 in providing a presser member located in that compartment of the drum in which the

clothes will be located when the partition is closed and means for actuating said presser member to squeeze the water out of the clothes. Another feature of the invention 60 consists in providing a movable cabinet case for the apparatus to entirely enclose the same when desired and in which the mechanism is mounted, said cabinet having suitable fittings for detachable connection with 65 a water faucet, the source of energy for supplying heat and for connection with motive power.

Other features of the invention will be more particularly described hereinafter 70 and claimed at the close of the specification.

The invention will be fully understood from the following description when taken in connection with the accompanying drawings, and the novel features thereof will be 75 pointed out and clearly defined in the claims at the close of this specification.

In the drawings:

Fig. 1 is a vertical sectional view of a washing machine embodying the invention, 80 showing the movable partition open, taken transversely of the drum.

Fig. 2 is a section on line 2—2 of Figure 3, showing the presser plate in position for squeezing the clothes. 85

Fig. 3 is a vertical section on the same line as Fig. 1, showing the movable partition closed and the clothes in the upper compartment.

Fig. 4 is a section on line 4—4, Fig. 3.

Fig. 5 is a fragmentary view on an enlarged scale showing a portion of the runway for the movable partition.

Fig. 6 is a fragmentary view on an enlarged scale in plan showing a portion of 95 the movable partition and its engagement with the runway.

Referring now to the drawings:

There is shown at 1 a metal water tank which as shown in the drawings is of rectangular contour enclosed in a cabinet 2.

The cabinet is preferably provided with legs 4 at the corners, said legs having casters 5 to enable it to be easily rolled about on the floor to position it wherever desired. 105

The tank is provided with a water inlet opening in one of its walls near the upper part into which is fitted a nipple 6 or other suitable fitting adapted to be connected by a suitable coupling with one end of a flexible 110 hose 7. The other end of said hose may be readily connected up with a faucet in the

- 22
- sink or other suitable source of water supply, not shown. The cabinet will also be formed with an aperture in alignment with the said nipple connection with the tank.
- 5 There is provided means for heating the water in the tank, the means shown in the drawings consisting of a gas burner 8 to which leads a pipe 9 passing in through the wall of the tank and cabinet near the top 10 somewhat above the water line and adapted for connection at 10 with a flexible gas pipe 11 which in turn may be connected with a gas fixture, not shown. Any other suitable heating device, however, may be employed.
- 15 The wash tub consists of a rotary drum 12, preferably of cylindrical form and made of metal, said drum having the two ends or heads 13, 14 and peripheral wall 15. The heads of the drum are provided with trunnions 16, 16, said trunnions being journaled in bearings in the upright leg portions 17, 17^a of a U-shaped frame having a base portion 18 connected to the upright portions, said base resting on the bottom of the tank.
- 20 The leg 17 is shorter than the leg 17^a, the bearing for the shaft in that leg being a U-shaped recess in the top of the leg so that the shaft can be dropped therein from above to enable the shaft to be mounted in 25 the bearings.
- 25 The leg 17 is shorter than the leg 17^a, the bearing for the shaft in that leg being a U-shaped recess in the top of the leg so that the shaft can be dropped therein from above to enable the shaft to be mounted in 30 the bearings.

The drum is revolvable on its trunnions within the tank. The periphery of the drum is formed with a large number of apertures 19 so that as the drum revolves and the 35 apertures come below the water level in the tank, the water will freely circulate through the said apertures into the drum and thereby maintain a water level in the drum, the same as the water in the tank. The proper water 40 level is shown at 20 slightly below the central axis of the drum.

The drum is provided with two doors 21, 22 in its periphery diametrically opposite each other through either one of which the 45 clothes may be introduced into the tub or drum, according to whichever is on the upper side. They will be removed through the door 21 as will be hereinafter described. When the clothes are to be introduced into 50 the drum, the drum will be adjusted so as to bring either the door 21 or the door 22 to the top. In the drawings the door 21 is at the top. When the clothes are to be removed after the washing and squeezing the 55 drum will be stopped after the rotation at a time when the door 21 will be at the top. These doors are preferably hinged as at 23 and are provided with a catch 24 for fastening them in closed position. There are also 60 provided means for securing the drum against rotation when it is desired to stop it either in the position for introducing the clothes or for taking them out. As shown in the drawings the periphery of the drum is provided with two loops 26, 27 at diamet-

rically opposite points and a hook 28 is provided at the top of the cabinet which is adapted to engage with either one of said loops as the case may be when the drum is stopped in the position to bring either the 70 door 21 or the door 22 at the top.

Any suitable means may be provided for rotating the drum. The preferable means is that shown in the drawings and is as follows: a gear wheel 29 is mounted on one of 75 the trunnions said gear wheel having driving connections with suitable driving means. As shown in the drawings said gear wheel is a bevel gear and engages with a bevel pinion 30 mounted on a shaft 31 journalled 80 in suitable bearings 32, 32, the other end of said shaft being provided with a bevel pinion 33 which engages with a bevel gear 34 mounted on a shaft 35, said shaft 35 carrying a sprocket wheel 36 which has a 85 sprocket chain connection 37 with a sprocket 38 mounted on a shaft 39 and which in turn has driving connection with a shaft 40 of a motor 41 by means of a sprocket 42, chain 43, a sprocket 44 mounted on a shaft 45 carrying a sprocket 46 over which runs a chain 47 which also runs over the sprocket 48 on the motor shaft 40.

Any other suitable form of driving connection, however, may be employed for driving the bevel gear 31. While the means for driving said shaft as shown in the drawings consists of an electric motor, any other kind of motive power may be employed.

In order to protect the gears both from the water and from outside interference, the cabinet is extended both at the back side and at one end and a partition 4^a is provided on the back side to form a chamber 50 for the gears and shafting on the back side, and a 105 partition 51 is provided at the end to form an end chamber 52 to enclose the gears and driving connections at that end.

The drum is provided with a movable partition which extends from end to end 110 of the drum so that the drum may be divided, when desired, into two compartments. In the form of construction shown, this partition is of a roller type, preferably formed in two parts 53, 53^a which slide in opposite 115 directions. Each member of the partition is preferably composed of rollers 54 laid parallel with each other and connected by links 55 in such manner that the partition is flexible. The rods are spaced slightly 120 apart from each other forming spaces 56 between them through which the water may flow out into the lower part of the drum when the drum is stopped in the position shown in Fig. 3, with the roller partition 125 closed. A run-way 57 for the said roller partitions is provided in each of the two heads 13, 14 of the drum by flanges 58, 59. One edge of each partition member is provided with handles 60 for the purpose of 130

manipulating the partitions to open and close them.

It will be noted that a portion of the run-way is semi-circular following the inside periphery of one half of the drum, and the connecting portion of the run-way, that shown at the top in Figs. 1 and 3, extends transversely of the drum slightly arched over the center of the drum. In order to allow for the proper construction of the run-way the peripheral wall of the drum is formed of two semi-cylindrical shells. One of said shells is of slightly less diameter than the other, the shell which is connected with that portion of the head in which the semi-circular portion of the run-way is formed being of the less diameter, the lower edge of the other shell which is the upper shell, when the drum is in the position shown in Figs. 1 and 3, slightly overhanging the lower shell.

This allows free clearance for the run-way and makes a thin space 61 between the lower edge of the upper shell and the upper edge of the lower shell when in the position shown in said figures.

When the said roller partitions are turned down into the positions shown in Fig. 1, the interior of the drum is all one compartment. This is the position that the partition should occupy preliminary to the introduction of the clothes for the purpose of washing. The cabinet is provided with a hinged cover 62 which should be kept closed except when the machine is about to be used.

A movable partition plate 63 of segmental form is mounted upon a feed screw 64 which extends longitudinally of the drum and has its ends journalled at 65 and 66. This plate is in a plane at right angles to the axis of rotation of the drum. The convex edge 67 of said partition plate follows the inner periphery of that shell of the drum which does not contain the roller partition and the concaved edge of said partition follows the curve of the upper edge of the flange 58 of the run-way, as shown in Figs. 1 and 3. One end 68 of the feed screw 64 is squared to receive a wrench and extends into the space between the end wall of the drum and the end of the tank. A hole 69 is formed through the wall of the tank in alinement with the said feed screw for the introduction of a socket wrench to engage with the squared end 68 of the feed screw to rotate said feed screw when desired.

The plate 63 is preferably formed with a strengthening rib 70 having at its outer end a lug 71 which is tapped out for the passage of the feed screw. By rotating the feed screw the said partition plate 70 may be moved in a lengthwise direction of the drum, that is, in a plane at right angles to the axis of the drum.

When it is desired to begin the washing

the hinged cover 62 will be thrown open then the door 21 or 22 of the drum will be opened, the hook 28 being engaged with the loop on the drum to prevent rotation. The clothes 72 will be introduced into the drum through said door 21 or 22 and will fall to the bottom of the drum. At this time the partition 63 should be in the position shown in dotted lines in Fig. 2, that is at the extreme end of the drum, the entire drum being now one compartment. Water will be admitted through the pipe 6 and the tank filled to the proper level.

The drum will then be rotated either by starting up the motor or by whatever means are employed for rotating the drum and the clothes will be tumbled about in the drum, the water having free circulation from the tank through the drum as already described.

The rollers 54 which make up the roller partition are cylindrical rods which extend the whole length of the drum next to the inner periphery thereof and these will aid in tumbling the clothes. When the drum has been rotated a sufficient number of times to give the clothes the proper amount of washing, the rotation of the drum will be discontinued when the drum is in the position shown diametrically opposite that shown in Figs. 1 and 3. The flattened portion of the run-way will then be on the underside. The operator should then grasp the handles 60 of the two members of the roller partition and move the two partition members into closed position. The clothes being in the then underside of the drum will be pushed down by the pressure of the said roller partition and be retained in that compartment of the drum. There should never be enough clothes in the machine at any one time to make the drum too full for this purpose. The drum should then be rotated a half turn so as to bring it around into the position shown in Fig. 3, the compartment containing the clothes being then on top as shown in Fig. 3 above the water level.

The socket wrench will then be applied to the squared end 68 of the feed screw and the feed screw should be turned in a direction to move the presser plate 63 from the dotted-line position shown in Fig. 2, at one end of the drum toward the opposite end as shown by the full-line position in Fig. 2. This will squeeze the clothes against the opposite end of the drum and the water will drip through the spaces between the rods of the roller partition into the lower part of the drum and thence into the tank. An outlet pipe 73 is provided in the lower part of the tank which should be opened to draw off the water. The tank is preferably formed with a sloping channel 74 in the bottom to carry the water toward the drain outlet.

When the clothes are sufficiently squeezed

the feed screw may be rotated in the opposite direction and the door 21 will be opened and then the clothes taken out.

What I claim is:

5. 1. A washing machine having a rotary drum to receive and tumble the clothes to wash them, a partition member within said drum which is movable at the will of the operator to divide the interior of the drum into two compartments so that the clothes when washed may be assembled in one of said compartments, a movable presser member located in the compartment in which the clothes are assembled and means for moving said presser member to push the clothes toward one end of said compartment and squeeze them.
10. 2. A washing machine having a water tank, a rotary drum mounted within said tank, a door for admission of clothes into the drum and for removal therefrom, a roller partition within the drum which may be adjusted to divide the drum into two compartments or moved back to make the said
15. 25. two compartments into one, a presser member located in one of said compartments and means for operating said presser member to squeeze the clothes in said compartment.
3. A washing machine having a rotary drum for washing and tumbling the clothes, said drum being apertured to permit the circulation of water into and out of the drum, a movable partition member which is movable at the will of the operator to divide said drum longitudinally into two compartments lengthwise of the drum, and a movable presser member located in one of said
30. 35. two compartments and movable toward one

of the heads of the drum to squeeze the clothes in said compartment between said 40 presser member and the head of the drum, said longitudinal partition being apertured to permit drainage of the water from the squeezed clothes when the said drum is stopped in its rotation in a position such 45 that the compartment containing the presser member is uppermost and means for moving said presser member to squeeze the clothes between said presser member and one of the walls of the drum.

4. A washing machine having a water tank, a rotary drum mounted within said tank, a door within the wall of the drum to permit the introduction and removal of the articles to be washed, the drum being apertured to permit water from the tank to freely pass in and out of the drum, a roller partition which may at will be adjusted to divide the drum longitudinally into two compartments or rolled back to make the 60 two compartments into one, and a presser member located in one of said compartments which is movable parallel with the axis of rotation of the drum to squeeze the clothes in said compartment between said presser 65 member and one of the heads of the drum, said roller partition having spaces through which the water will drain out of the said presser compartment when said partition is closed and the drum is turned on its axis 70 to bring the compartment containing the clothes and presser member into its uppermost position.

In testimony whereof I affix my signature.

NICOLA MASTROMARINO.
